HYDRAULIC FLUID LIFT

Robert E. Shappell, Wichita Falls, Tex.

Application July 22, 1931, Serial No. 552,426

1 Claim. (Cl. 60—52)

This invention relates to oil well pumping apparatus and equipment and it has particular reference to new and novel improvements in hydraulic pump jacks.

5 The primary object of the invention is to accomplish through the medium of fluid under pressure that which has heretofore been done mechanically and in so doing, the invention seeks to materially reduce the cost incident to the 10 pumping of fluid from wells, yet with increasing volume compared to the lowered cost of pumping.

The invention, through its novel arrangement of elements defines an improved method of elevating fluid from wells, which method involves the use of a fluid pressure medium separate from the fluid pumped from the well and which fluid pressure medium is circulated in such manner as to have an effect upon the pumping equipment for elevating the fluid from the well.

Another object of the invention resides in the provision of an actuating valve and an attendant controlling valve, both of which are automatically operated by fluid under pressure and 25 are cooperative in the sense that they are both required for the effective pumping of fluid from the well.

Still another object of the invention resides in arranging the elements of the combination so 30 that the polished rod will move in a strictly vertical line, which removes the possibility of crystallizing the polished rod to such an extent that it may easily break and allow the sucker rod assembly to fall into the hole and which would 35 necessarily require an expensive job. This annoying condition exists in a great number of mechanical pumping jacks which are not constructed so that the polished rod may move vertically.

40 Broadly, the invention includes hydraulic rams carrying a crosshead which is operatively connected to the polished rod and further includes a sliding valve, automatically operated by a trip which is actuated by the movements of the rams. 45 The invention further includes in its arrangement a fluid pressure control valve operated in accordance with the above mentioned valve so as to intermittently control the pressure from the pump during upward and downward movements 50 of the rams.

With the foregoing objects as paramount, the invention has particular reference to its salient features of construction and arrangement of 55 parts which will become manifest as the descrip-

tion proceeds, taken in connection with the accompanying drawings, wherein:

Figure 1 is a perspective view of the complete assembly showing the operating valves.

Figure 2 is a longitudinal sectional view of the 60 operating valves, and

Figure 3 is a diagrammatic plan view showing the method by which fluid is circulated under pressure for actuating the pumping rams.

Continuing more in detail with the drawings, 65 it may be first mentioned that the conventional mechanical pumping jack is operated by rigid or flexible means by an engine remotely situated. Usually, a number of these jacks are operated from the same source. The pump lines frequently break and it has been found to be a difficult matter to re-connect them for further operation which causes a considerable loss of time.

Moreover, a conventional pumping jack employing strictly mechanical elements is not usually constructed so that the polished rod may move vertically, thus crystallizing the rod and causing ultimate breakage.

The present invention, in making use of fluid under pressure does not require alinement with 80 the source of power and may therefore be constructed to suit any condition under which it is elected to operate, nor is there a likelihood that it will be disconnected from the power source and accordingly become inoperative. All of these 85 vitally important matters taken together represent the saving both in the cost of operation and in the loss of time during inoperative periods.

Accordingly, 1 designates a pair of vertically disposed ram casings in which the rams 2 are 90 mounted for vertical movement and are shown in Figure 1 in the lowest position. A crosshead 3 is connected to the rams which, in turn engages the polished rod 4. An arm 5 is rigidly connected to the crosshead 3 and is provided with a brace 95 6 so that there will be no lateral displacement of the outer end of the arm 5 which is so constructed as to slidably engage a vertical rod 7, to which reference will be later made.

Again referring to the rams, a brace member 100 8 maintains rigidity of the ram casings 1 relative to the casing head 9 and the discharge pipe 10 leading from the well to a suitable storage tank at some remote point not herein shown.

It is of course the object of the present invention to vertically reciprocate the polished rod 4 without any side movement whatsoever from the perpendicular. In order to do so the rams 2 must be raised and lowered with equal precision and without any variation in movement. In so do- 110

ing, the crosshead 3 to which the polished rod 4 is securely affixed by means of clamps 11, moves in a straight line to so move the polished rod 4, to which the sucker rod assembly and pump valves 5 are suspended in the well. At each stroke of the polished rod, the fluid in the well is brought to the surface and discharged.

The principal elements of the present invention, as stated in the foregoing include an actuating valve and a control valve, to be referred to in detail later and which are mounted upon the platform 12. Mounted also upon the platform 12 at the end next to the well are a pair of uprights 13 and joined together by strips 14 to provide a guide for the vertically reciprocating bar 15. A spring 16 holds the bar in a vertical position when it is reciprocated in the manner later explained. A roller 17 is mounted upon the lower end of the reciprocating bar 15 and serves the important function of operating the actuating valve within the housing 18, through the medium of the trip 19. The trip 19, as apparent in Figure 1, is provided with oppositely extending arms terminating in a fork 20 which is pivoted at 21 between a pair of uprights 22, which are also mounted upon the platform or base 12. A roller 23 is likewise mounted between the upper ends of the uprights 22 so as to afford a nonfrictional bearing surface against which the fork 20 impinges when rocking motion is imparted to the trip 19 by the reciprocating movements of the bar 15. Braces 21a jointly support the uprights 13 and the uprights 22. These braces are rigidly anchored to the base 12 at 24 as apparent in Figure 1.

A brief explanation will be given at this point concerning the relationship of the valves, the communicating pipes and the like and each of the elements referred to at this point will be identified by reference characters and a complete description bearing these and other reference characters will be later given concerning the individual and collective function of the valve.

The actuating valve housing is designated at 18 and has fluid communication with the adjacent valve only through the pipe 25 having a cut-off valve 26 therein. However, an adjustable piston rod 27 enters each of the valve housings 18 and 28. The pipe 29 which is seen in Figure 1 as entering the top of the valve casing 28 is the pump line through which the fluid pressure operating medium is first introduced in the valves, which will be later explained. It will also be understood that a reservoir 30 is provided and is situated at a remote point from the apparatus. A pipe 31 entering the valve casing 18 communicates with a pipe 32 which latter is a return line to the reservoir 30. Also communicating with the return line 32 is a pipe 33 which communicates with a port within the controlling valve and which will be later referred to in the description of the valves. A pipe 34 serves as a means by which the fluid actuating medium is introduced in the ram chambers 1 for actuating the rams 2 and it also has communication with the control valve situated in the chamber 28. Another drainage pipe 35 serves also as a fluid return line and functions to relieve pressure upon the control valve or, in other words to maintain uniformity of pressure on both the valves so that they will be prepared to operate quickly when called upon to do so by the movements of the rams and the action of the pump 36, shown in Figure 3.

As stated in the foregoing the brief description just concluded is given merely to identify the

several parts relating to the valves in the housings 18 and 28 and the description to follow will include some of the elements named so as to identify them with those not hereinbefore referred to in describing the function of the valves shown in Figure 2. With particular reference to Figure 2, it will be noted that valve housing 18 is centrally cored to receive a piston 37, which is mounted upon the end of piston rod 27. The upper portion 38 of the valve casing is mentioned to receive the sliding valve 39 which is in control of ports, a, b, c and d within the portion 18 of the valve. It will be observed that movement of the valve 39 will change the fluid passages by opening and closing these ports.

To operate the sliding valve 39, a rod 40 is threadedly connected to the valve and passes through a packing gland 41 to the exterior to be engaged by the fork 20, which as mentioned previously is an integral part of the trip 19 and whose operation will be later explained. Referring now to the companion valve which is represented as the control valve, the base 42 is cored at spaced intervals to receive the pipes 33, 34 and 35, whose function will be also explained later. The housing 28 in the valve is machined to receive the sliding valve 43, which is connected to the opposite end of the piston rod 27, which as previously explained enters the bore in the adjacent valve casing 18 through the packing glands 44 and 45.

The foregoing brief description of the valves is believed to be sufficient, taken together with the following description of operation, to fully understand their individual and collective function in the pumping of a well.

Accordingly and in operation, it will be assumed that the rams 2 are in the lowest position as shown in Figure 1. In this position fluid from the pump 36 is pumped through the line 29 to enter the chamber 46 of the control valve. The valves 39 and 43 are shown in Figure 2 as being set to allow passage of fluid directly through the pipe 34 to the rams 2, since the port e in the chamber 46 is open. It will be noted also that the chamber 47 in the actuating valve is open to the port c, which communicates with the chamber 48 in the cylinder in which the piston 37 travels. Fluid from the pump 36 is passed through the pipe 29, into the chamber 46 of the control valve, through the port e and the pipe 34 into the ram casings 1 1. This is clearly shown in the diagrammatic view in Figure 3. Thus pump pressure acts directly upon the rams 2, thereby raising them simultaneously and bringing the crosshead 3 to the highest position and thereby elevating the sucker rod assembly.

When the crosshead 3 reaches its highest position, or just before, the outer end of the arm 5 will impinge the rod clamp 49. This action will bring about a vertical pull upon the rod 7, which will elevate the bar 15 to such an extent that the roller 17 carried thereby will move to engage the upper arm of the trip 19. When this is done the fork 20 will be moved on its pivot 21 to the dotted line position shown in Figure 2.

Obviously a pull is exerted upon the rod 40 which will move the sliding valve 39 in the chamber 47 to close the port c and open the port d to the port f through the medium of the chamber g in the valve. The port f communicates with the pipe 31 previously referred to and which is a return line to the reservoir 30. The sliding valve 39 is thus mechanically forced to close the port c, open the port d for drainage, close the port b and open the port a. When the port a is opened, fluid

- under pressure enters the chamber 50 and thereby actuates the piston 37 to expand the chamber 50. Thus a pull is exerted upon the piston rod 27 simultaneously with the introduction of fluid 5 under pressure into the chamber 50, thereby moving the sliding valve 43 to communicate the port *e* with the port *h* in the adjacent control valve through the medium of the chamber 51 in the valve 43.
- 10 From the foregoing it will be seen that pressure from the pump 36 is bypassed through the port *i*, which is opened when the valve 43 is moved to the dotted position shown in Figure 2, by reason of the movement of the piston rod 27. Fluid under 15 direct pump pressure passing into the chamber 46, port *i* in the pipe 35 returns to the reservoir 30 for recirculation through the pipe 52, which communicates the reservoir 30 with the pump 36.
- A valve 53 is in control of the line 35 which 20 functions as a release pressure valve and is set manually to retain the pressure on the automatic valve 43, to hold it to its seat, to operate the piston 37 on the next stroke and also maintain equal pressure in the lines 29 and 25.
- 25 It has been stated that fluid pump pressure is relieved by opening the chamber 46 to allow the fluid operating medium to return to the reservoir for re-circulation. At the same time, fluid in the chamber 48 of the actuating valve, forwardly of 30 the piston 37 is forced through the port *d*, chamber *g* and out through the port *f* into the line 31, which also returns the fluid to the reservoir 30.
- The rams being in the highest position are beginning their downward stroke and the fluid in 35 the casings is required to be expelled. Accordingly, the fluid passes back through the ram lift line 34, as apparent in Figure 3 and enters the chamber 51 in the valve 43 thence enters the port *h* and into the pipe 33, which communicates with 40 the return line 32 to the reservoir 30.
- From the foregoing, it is very apparent how 45 the fluid from the pump 36 enters the pipe 34 to elevate the rams. It also brings out the important feature of draining the actuating valve and the control valve preparatory to the lowering action of the rams. When the rams have returned to their lowest position, the outer end of the arm 5 impinges the rod clamp 54, which is spaced from the clamp 49. When the clamp 54 50 is depressed, the fork 20 urges the rod 40 inwardly as apparent in Figure 2 and thus returns the sliding valve 39 to the position shown in solid lines in Figure 2.
- When this occurs, the pump pressure through line 25 fills the chamber 47 of the actuating valve and flows through the port *c* to the chamber 48. Fluid pressure upon the piston 37 then urges the sliding valve 43 to the position shown in solid lines and simultaneously expels fluid from the chamber 50 of the actuating valve through the port *b*, the chamber *g* and the port *f* into the return line 31. In this position pump pressure exerted upon the fluid in line 29 will again cause the same to flow through the ram lift line 34 for another operation in lifting the rams 2.
- It will be understood that there is no change in the operation of the pump 36, since the latter keeps the operating fluid in circulation, until the actuating valve is mechanically operated with timed precision to effect the raising and lowering of the rams.
- Manifestly, the construction shown and described is capable of considerable modification and such modification as is considered within the scope and meaning of the appended claim is also considered within the spirit and intent of the invention.
- What is claimed is:
- A pumping apparatus comprising the combination of a pair of fluid actuated rams, a fluid supply reservoir, a valve chamber containing a sliding valve, a horizontally disposed cylinder below said valve having communication with said valve chamber, a piston in said cylinder, a second valve chamber, a sliding valve therein, a horizontally reciprocating rod connecting said latter valve with said piston, each of said valve chambers having communication with said fluid reservoir, means for pumping fluid from said reservoir through said second valve chamber to lift said rams, means operative to positively move said first valve upon the raising of said rams to cause the fluid pressure from said pumping means to be directed against said piston to actuate said second valve, thereby to close the means of communication between said pumping means and said rams, means to effect return of fluid to said reservoir to return the fluid pressure on said rams and means to again change the positions of said valves upon the lowering of said rams.
